TELEPHONE SYSTEM

William Gibson Stanley, New York, N. Y., and Frank Augustus Leibe, Quakertown, Pa., assignors to Federal Telephone and Radio Corporation, New York, N. Y., a corporation of Delaware

Application May 12, 1943, Serial No. 486,630

15 Claims. (Cl. 179—43)

This invention relates to a ringer for use in connection with telephone switchboards, whereby the customary low ringing frequency of around 20 cycles is transformed into a higher frequency lying within the voice range, such as 500 or 1000 cycles. This higher frequency can readily pass over transmission lines, along which apparatus such as repeaters or carrier telephone circuits may be placed, due to the fact that such pieces of apparatus are designed to pass frequencies of 500 or 1000 cycle, whereas they frequently are not capable of efficiently passing a frequency as low as 20 cycles. Suitable conversion apparatus at the receiving end of the transmission line converts the 500 or 1000 cycle ringing current back into the usual 20 cycle current, for operating switchboard or other terminal apparatus, customarily designed for such relatively low frequency ringing current.

One purpose of this invention is to provide an assembly of various cooperating units for insertion at the sending end of a transmission line, between the operator's ringing key and the line proper. At the receiving end, a similar unit is inserted between the line proper and the drop or other indicating device employed.

A further object of this invention is to provide, in a single assembly, apparatus of the type above-described, which will be capable of automatic two-way operation, so that such apparatus will, without manual switching, perform the frequency conversion function at the sending end of the line, in a direction from low to high frequency and at the receiving end of the line, will perform the frequency conversion in the opposite direction.

Yet another purpose of this invention is to provide apparatus of the type above-described, which can easily and quickly be inserted into a transmission line, at both sending and receiving ends thereof, and without causing undue loss or weakening of speech frequency currents.

A still further purpose of this invention is to provide, at the receiving end of a transmission line, apparatus which will be able to differentiate between frequencies of 500 or 1000 cycles as occurring at random intervals during the course of speech transmission, and a 500 or 1000 cycle current intentionally used for ringing purposes, or any other frequency or narrow band of frequencies used for signaling purposes or the like, whereby undesired or false operation of the ringing or signaling elements of such receiver during voice transmission is avoided.

The complete ringer assembly of the present invention is a device employing electronic tubes

as oscillators, amplifiers and detectors and it also includes a power supply unit affording the potentials and currents necessary for the operation of such tubes, as well as for the operation of rectifiers, relays and other elements of the assembly.

The device of this invention affords a ringing current for transmission purposes, having a frequency of 500 or 1000 cycles and optionally modulated at about 20 cycles, this ringing current being demodulated at the receiving end and determining the application of a 20 cycle current thereto. The construction and operation of this apparatus may be better understood by reference to the drawings herewith, where:

15 Fig. 1 is a block schematic diagram of a circuit embodying two complete ringer assemblies according to this invention, located at the respective ends of a transmission line.

20 Fig. 2 is a detailed schematic diagram of the 20 cycle rectifier unit employed in a ringer assembly, according to this invention.

Fig. 3 is a detailed schematic diagram of the oscillator unit, similarly employed.

25 Fig. 4 is a detailed schematic diagram of the receiver unit, similarly employed.

Fig. 4(a) shows an alternative method of connection of the feed-back circuit between tubes V2 and V3 of Fig. 4.

30 Fig. 4(b) shows an alternative form of filter which may be used in one portion of the circuit of Fig. 4.

Fig. 5 is a detailed schematic diagram of a power supply unit which may be employed with the ringer of this invention.

35 Fig. 6 is a detailed schematic diagram of a single complete ringer unit, exclusive of the power supply, according to this invention, as used either at the sending or the receiving end of a transmission line.

40 Fig. 7 is a graph showing the frequency-voltage relations in one filter element of this invention.

In all the figures of the drawings, certain relays have the armatures thereof shown separated by some distance from the magnet thereof, for the sake of greater clarity in illustrating the circuits. However, such armatures are shown in alignment with the magnets of the particular relay to which they belong, so that the identification of such relay with its own particular armatures is unmistakable.

Referring now to Fig. 1, there is here illustrated a complete transmission circuit, with respect to ringing signalling, and including a portion of the associated switchboard elements at both the sending and the receiving ends. The elements shown

at the left represent a ringer with the various elements in the positions which they assume when such ringer is functioning as a transmitter, while the apparatus shown at the right end of this figure illustrates a similar ringer, but with all the elements thereof in the positions which they assume when the ringer is functioning as a receiver.

At the sending end, the switchboard drop 101 is illustrated, but is inoperative, since it is disconnected from the line by the position assumed by the right hand portion of the operator's ringing key 102. The position of this ringing key places upon the input of the ringer the approximately 20 cycle ringing current available at the switchboard, as indicated by the legend appended to the upper right hand portion of ringing key 102.

At 103 is indicated a source of 20 cycle current, shown in detail in Fig. 3. At the sending end, this source of 20 cycle current is not directly connected to the line at the sender, because the output circuit thereof remains open at the contact points of relay 107, armatures 1 and 2, the action of which relay will later be described.

At 104 is indicated a receiver, shown in detail in Fig. 4, which remains in an inactive state at the sending station. Relay 107 is excited only by the output of receiver 104 and accordingly, when sending, all the armatures of this relay remain in the respective open positions indicated. This allows the 20 cycle current from the operator's key to flow through armature 1 and contact *a* of relay 107, as well as through armature 2 and contact *d* of the same relay. The 20 cycle current thus reaches rectifier 105, shown in detail in Fig. 2. This rectifier is at all times bridged across the transmission line, but is so designed as to present a comparatively high impedance to voice frequencies, so as to cause only a negligible loss to the voice current on the line. However, the rectifier is designed to have high acceptance for the 20 cycle ringing current, impressed upon it at the sending end.

As later explained in detail in connection with Fig. 2, rectifier 105 acts to rectify the 20 cycle current and gives an output of direct current to the winding of relay 108. The excitation of relay 108 causes armature 1 of this relay to move downwardly to contact *g* and armature 2 to move upwardly to contact *i*. These contacts just referred to are connected to the output of oscillator 106, also shown in detail in Fig. 3. This oscillator is set into action by the transference of armature 3 of relay 108 from contact point *k* to contact point *j*, as later described in detail in connection with Fig. 3.

The connection of oscillator 106 to the transmission line is likewise accompanied by the disconnection of the line from other portions of the sending ringer, due to the opening of contact *f* and *h* at armatures 1 and 2 respectively, of relay 108. Oscillator 106 is arranged to produce a current lying in the voice frequency range, such as 500 or 1000 cycle and optionally modulated at 20 cycle, as hereinafter explained in connection with Fig. 3. Accordingly, the transmission line proper is now supplied with the voice frequency current produced by oscillator 106.

Referring now to the right end or receiving portion of Fig. 1, oscillator 106 is there disconnected from the line, due to the open positions assumed by armatures 1 and 2 of relay 108. Relay 108 is, of course, not excited by rectifier 105, due to the fact that no 20 cycle current is present

on the line which feeds this rectifier. Receiver 104, however, is shunted across the path of the incoming ringing signals of voice frequency, and is designed to be selectively activated by such signals having a predetermined frequency, as later explained in connection with Fig. 4. The ringing signals of voice frequency picked up by receiver 104 are suitably amplified and rectified so as to cause the excitation of relay 107 at the receiver. The excitation of relay 107 causes the line to be opened up at armatures 1 and 2 of this relay, which are moved from contact *a* to contact *b* and from contact *d* to contact *e*, respectively.

15 Contacts *b* and *e* are connected to 20 cycle source 103 at the receiver and the closure of armature 3 of relay 107 against contact *c*, initiates the operation of 20 cycle source 103. The output of 20 cycle current derived from source 20 103 traverses ringing key 102 which, in the non-ringing position shown, causes the 20 cycle current ultimately to reach drop 101, or other suitable indicating device provided at the receiver and designed to be operated by the customary 20 cycle ringing current.

With reference to the description of the other figures of the drawings, it is to be noted that certain values of electrical constants are given in connection with various elements thereof. It is to be understood that such values are merely illustrative and may be subject to considerable alteration, as will be apparent to one skilled in the art. Likewise it is to be understood that certain specific frequencies herein mentioned, e. g. 20 cycle, 500 cycle and 1000 cycle, are merely chosen as illustrative, and that if one of these frequencies takes on a different value, there will be needed corresponding changes in the electrical constants of certain elements of the circuit, such as inductances and capacities.

Reference is now made to Fig. 2 of the drawings, illustrating the 20 cycle rectifier in detail, and its interconnection to other elements of the ringer assembly.

45 Across the line coming from the switchboard is bridged a circuit tuned to approximately 20 cycles. This circuit comprises the inductance presented by the windings of transformer 201 and the capacity of condenser 202.

This circuit is in series with a rectifier 203, preferably of the full wave bridge type. The D. C. output path of this rectifier preferably contains a smoothing condenser 204 and feeds the winding of relay 108, as previously explained.

55 Tuned circuit 201, 202, while offering a comparatively low impedance to the 20 cycle current coming from the switchboard, yet will present such high impedance to voice signaling currents upon the line as to impose a negligible load with respect to such voice currents, this point being an important one because of the fact that the tuned circuit is at all times bridged across the transmission line.

The operation of relay 108 will cause armatures 1 and 2 thereof to disconnect the switchboard output from the line and will cause them to connect oscillator 106 to the outgoing line, the reason for this connection having previously been explained in connection with Fig. 1.

70 Contact *j* at armature 3 of relay 108 is here shown connected to a terminal 205. When the rectifier unit is put into a complete assembly, a conductor from terminal 205 will afford connection to a contact of relay 107 and to 20 cycle source 103, as illustrated in Fig. 1. Contact *k* at

armature 3 is connected to two points, as indicated by the respective legends in Fig. 2. One connection is to the cathode of certain tubes in receiver 104, for purposes which later will be explained in connection with Fig. 4. The other connection from contact *k* is extended through a suitable resistor 206 to the screen of the tube in oscillator 106, for reasons later to be explained in a detailed discussion of this oscillator.

Making reference now particularly to Fig. 3, the portion of this figure to the left of the dotted line represents an oscillator of the mechanical vibrator type, yielding a low frequency, such as 20 cycle. To the right of the dotted line is shown an electronic tube oscillator giving an output of voice frequency, such as 500 or 1000 cycle. While these two units are here shown as adjacent to one another, in order that their mutual electrical interaction may be more clearly understood, yet it is to be understood that such arrangement is not essential, but that the mechanical vibrator may be placed in any location desired, for example in the power supply unit.

The mechanical vibrator 301 has the driver magnet 302 thereof fed by the direct current derived from rectifier 303, this latter being preferably of the full wave, bridge type. This rectifier is, in turn, fed from the secondary winding of transformer 304, the primary winding of this transformer being fed with a suitable supply of alternating current, as later to be explained in detail in connection with Fig. 5.

The output of rectifier 303 is smoothed by condenser 305 and the completion of the circuit through driving magnet 302 of vibrator 301 is obtained only when the positive terminal of the rectifier output is connected to ground, as will be apparent from the connections of magnet 302. The 20 cycle output of vibrator 301 is fed into the mid-tapped primary winding of transformer 306. The secondary winding of this transformer is shunted by a suitable capacity 307 and resistor 308. Transformer 306 is designed to afford a secondary output of approximately 80 volts at about 20 cycle, which output appears across terminals 309.

The electronic oscillator of Fig. 3 includes a screen grid tube V₅ which may be of the type commercially known as 6G6-G, or other suitable type. This tube serves to excite a tuned circuit consisting of the primary winding of transformer 310, having a portion or all of the winding shunted by a capacity 311, sufficient to make the circuit resonant either to 500 or 1000 cycles, as may be desired. The frequency may conveniently be determined by the operation of a switch 312, the two arms of which are here shown as separated, for convenience in illustration, but which arms are simultaneously operable. This switch may be mechanically coupled with any or all of the switches utilized for frequency changing at other points of the system.

The anode supply for the electronic tube is fed through the mid-point tap of transformer 310, and may be secured from the power supply shown in Fig. 5. The oscillatory circuit is connected to the anode of the tube and, via a suitable condenser 313, to the control grid of the tube. This grid is likewise connected through two resistors 314 and 315, to the left hand terminal of the primary winding of 20 cycle transformer 306.

When the oscillator is not in operation, i. e., when the sending operator's ringing key is not depressed, the screen grid of tube V₅ is grounded

through resistor 206, armature 3 and contact *k* of relay 108 (Fig. 1). This grounding of the screen grid, keeps the oscillator tube in a quiescent condition.

When the sending operator's ringing key is depressed, the 20 cycle current derived therefrom is rectified by element 105, and relay 108 is excited, as described in connection with Fig. 1. The excitation of this relay causes armature 3 to leave contact *k*, thus removing the ground from the screen grid of tube V₅, and thus leaving this tube and associated circuits free to oscillate, since the screen grid will then secure proper positive potential, through resistor 206', from the high potential anode supply marked +180.

Armature 3 then places a ground upon contact *j*, to which contact is connected the positive side of the output of rectifier 303. As previously explained, this completes the energy supply circuit of vibrator 301, thus setting the vibrator into operation.

When the vibrating element 317 makes connection with the left hand contact 318, a connection to the ground is thus afforded for the control grid of tube V₅. The electronic oscillator will then be set into operation at a frequency of either 500 or 1000 cycles, according to the position assumed by switch 312. When vibrating element 317 makes contact with the right hand terminal 319, current flows from the ground portion of the primary winding of transformer 306, through rectifier 303, through contact *j* of relay 108 to the ground. This generates a voltage between the outside primary terminals of transformer 306, which acts to impress upon the grid of tube V₅, a negative bias sufficiently great to stop the oscillation of this tube, during the time while such contact remains closed.

As a result of this interaction of the mechanical vibrator and the oscillator, the 500 or 1000 cycle output of the oscillator is modulated at 20 cycle, and such modulated output appears across the secondary winding of transformer 310. This modulated output is variable by a network of suitable series and shunt resistors, 310', adjustable by a switch 350 (preferably coupled to switches 312), as indicated in Fig. 3, so that the output will be substantially constant at either 500 or 1000 cycle. Switch 351 changes the power level so that it will be either zero db. or +6 db., these particular power levels being purely illustrative. The details of such networks are well known in the art, and therefore detailed description thereof is deemed superfluous.

A rectifier 320 is shunted between the connection point of resistors 314 and 315, and the ground. This rectifier functions to smooth out irregularities in the modulated voice frequency output wave, for example those which may be produced by the effect of the 20 cycle vibrator contacts. The final modulated output at voice frequency appears across terminals 321, which are extended so as to connect to contacts *g* and *i* of relay 108, as shown in Fig. 1.

There are indicated in Fig. 3 certain cathode heating circuits, by-pass condensers and other elements ancillary to the operation of tube V₅. Such elements are well-known in the electronic tube art and a detailed discussion thereof is accordingly thought to be unnecessary.

Reference is now made especially to Fig. 4 which illustrates the receiving device used to pick up the voice frequency ringing signals from the transmission line and reconvert them into

a local 20 cycle, or similar low frequency current, which latter current is capable of actuating the conventional ringing signal apparatus designed for operation by such low frequency.

The receiving apparatus here shown is capable of receiving a voice frequency signaling current of uninterrupted or unmodulated character, but is likewise responsive to the signaling current of voice frequency, modulated at 20 cycle, such as that produced by the oscillator unit of Fig. 3. In some instances it may be desirable to use a non-modulated ringing signal current with a ringer according to this invention, and the receiver of Fig. 4 is accordingly flexible in its operation, so as to utilize either type of ringing signal.

As may be seen from Fig. 1, the receiver is bridged across the line during speech transmission and accordingly it is necessary to provide means for effectively preventing the operation of the receiver due to the presence during speech transmission of random frequencies, corresponding to the 500 cycle or 1000 cycle or other predetermined frequencies used for ringing or for other signaling purposes. As the point of origin of such speech frequencies may be situated, from an electrical viewpoint, very near the receiver, the energy due to such speech frequencies may be equal to, or even much greater than, the minimum energy required to operate the receiver, especially when the latter is adjusted to a degree of sensitivity sufficient to enable its operation over a relatively long transmission line. Likewise, random pulses of short duration frequently occur in such transmission systems, as, for example, from the operation of a switch hook or the like.

In order to make more certain that the receiver will respond only to the desired ringing signals, the receiver employs a number of devices to differentiate between the random impulses above referred to and the intentional ringing signals. A time delay element, incorporated in the receiver, helps to secure such selective actuation of the receiver, but has not in itself been found in practice to be a sufficient safeguard for the prevention of undesired actuation of the receiver.

The receiving unit illustrated in Fig. 4 accordingly is arranged to incorporate not only the time delay circuit above referred to, but is arranged also to incorporate a two-path transmission network. One path is very sharply tuned to the predetermined ringing frequency, while the other path is designed to pass substantially all the remaining frequencies which may be present upon the line, e. g. the other voice transmission frequencies occurring during speech transmission. The respective outputs of these two paths are suitably and individually detected and then are differentially combined, in such manner that an amplifier tube fed by this combination of both the detected signals will respond only when the greater portion of the energy which it receives comes over the sharply tuned transmission path of the network, i. e. when the energy is concentrated about the single ringing frequency.

It has been found that the arrangement above described, including the time delay circuit, will act in an extremely satisfactory fashion in preventing false operation of the receiver, even when such receiver has a degree of sensitivity sufficient to respond to ringing signals transmitted over about 30 db. of transmission line.

The input to the receiver, derived from con-

tacts *a* and *d* of relay 407 feeds the primary winding of transformer 401. Since this primary is bridged across the transmission line during speech transmission, the transformer is preferably made of high input impedance, in order to avoid undue bridging loss for speech transmission. It has been found desirable to include condenser 401' in the primary circuit, in order to prevent a metallic bridging of the transmission line. It also has been found that a transformer with an impedance ratio of 10,000:500,000 will impose negligible loss upon the line, but other values may be used. The secondary of transformer 401 is shunted by resistances 402 and 403 connected in series. The gain control switch 404 is arranged as indicated, so that the effective output potential of transformer 401 can be chosen to assume three different relative values. When switch 404 is placed on the point marked High, the maximum output of the transformer is available, such selection being made when the receiver must be operated over a transmission line of such length or other characteristics as to make the highest degree of sensitivity at the receiver advisable. When switch 404 is placed on the position marked Low, the sensitivity is reduced by about 15 db. The point marked Zero is used when it is desirable to prevent operation of the receiver, such condition being encountered, for example, when testing is being done upon the receiver itself, or upon the transmission line to which it is connected.

The output of transformer 401 is suitably amplified by an electronic tube *V*₁. The usual energy feeding and bias determining elements associated with this tube are indicated in Fig. 4, but a detailed description thereof is thought unnecessary, as such elements are well-known in the art. The output of tube *V*₁ is divided through a suitable resistive network including resistors 405 and 406, so that a portion of the energy is fed to the two respective transmission paths, above described. In the drawings, the arrows marked *A* and *B*, respectively, show these two transmission paths, path *A* starting at the end of resistor 405 connected to the anode of tube *V*₁, while path *B* starts at the junction between resistors 405 and 406.

Transmission path *A* and all the elements thereof, except the switching devices, are preferably enclosed in a shielding container 407, indicated by dotted lines. This shielded transmission network includes inductance and capacitance elements forming two sharply tuned circuits, the coupling elements necessary to transfer energy from one circuit to the next, and an output load resistance for transferring the output to the detector tube *V*₂, fed by the energy received over transmission path *A*. Voltages appearing across the output terminals of the network are impressed upon the load resistor 419 and upon the grid of detector tube *V*₂. The frequency vs. voltage characteristic across the network output terminals is shown by the appropriate curve in Fig. 7. Fig. 7 also shows the curve of frequency-voltage which appears across the network input terminals. The voltage appearing across the network input terminals is impressed in whole or in part upon the grid of detector tube *V*₂, through the coupling condenser 408. The ratio of the resistance of 405 to 406 determines whether the whole or only a fraction of the voltage appearing across the input terminals is impressed upon the grid of *V*₂. The reasons for impressing upon path *B* only a frac-

tion of the network input voltage will be later given.

It can be seen from the frequency-output voltage curve of Fig. 7 that the voltage applied to the grid of V_2 via path A will be substantially at a maximum for a narrow band of frequencies grouped around the signaling frequency and the output voltage will have a reduced value for all other frequencies outside this narrow band. It will also be evident from the characteristic frequency-input voltage curve that the voltage applied to the grid of detector tube V_3 via path B will be at a minimum over a narrow band lying near the signaling frequency and will have an increased value for all other frequencies lying outside this narrow band. Suitable switches are provided for changing the frequency discrimination from 500 to 1000 cycles, or to such other voice frequencies as may be employed. These switching devices are indicated by the numeral 407, and they may be mechanically coupled with switches 312 and 350, already described in connection with Fig. 3, so that one switching operation will change frequencies throughout a complete unit.

Transmission path A acts, then, to accept the principal portion of the energy entering the receiver at the predetermined signaling frequency, such as 1000 cycles, and substantially to reject all other frequencies. Currents passing through path A are detected by electronic tube V_2 . Condenser 418 and grid leak resistance 419 allow the proper rectifying action of detector tube V_2 to be obtained. Transmission path B, on the other hand, due to the decreased voltage across its input, acts virtually to reject a small band of frequencies around the predetermined signaling frequency and to accept all other frequencies outside this narrow band. Currents passing through path B are detected by electronic tube V_3 . Condenser 408 and grid leak resistance 409 secure the proper rectifying action of V_3 .

Transmission path B functions to prevent operation of the receiver from voice currents in which random frequencies corresponding to the predetermined signaling frequency may be present and may be termed a guard circuit. In this invention, the inductance and capacitance elements in the four terminal network serve the dual purpose of providing a band pass frequency discriminating network for path A and a band rejection discriminating network for path B. By thus taking advantage of both the input and output voltage characteristics of the network, the network elements of inductance and capacitance are employed to secure the desired results in an economical manner. This constitutes a definite improvement over other proposed signaling systems in which one set of elements is required for the band pass path and a separate set of elements is required for the band rejection path. The necessary relationships between the various sections of the network and the manner in which the sections may be adjusted to obtain the desired input and output voltage characteristics will be later explained.

The anodes of electronic tubes V_2 and V_3 are coupled through a resistance network comprising fixed resistors 410 and 411, together with variable resistor 412. The values of resistors 411 and 412 are such that the total resistance presented by the two in series may be adjusted so as to be equal to that of resistor 410, or so as to differ slightly therefrom, for reasons hereinafter to be explained. The anode power supply is fed to

the connection point between resistors 410 and 411 and is here shown as derived from the power supply unit, illustrated in detail in Fig. 5. This power supply unit is also indicated as furnishing the other necessary voltages to various elements of the receiver.

The end of resistor 410 nearest the anode of tube V_2 is likewise connected to the control grid of an output tube V_4 through a suitable resistance 10 413, while the anode end of resistor 412 is also connected through a suitable resistor 414 to the cathode of tube V_4 . The difference in the voltage drop in the anode resistors connected with tubes V_2 and V_3 , respectively, is in this fashion bridged 15 across the cathode and control grid of tube V_4 . Resistor 412 is adjusted until this difference of voltage causes the control grid of tube V_4 to become sufficiently negative so that the anode current of tube V_4 , which is supplied through the winding of relay 107, is reduced to a value sufficiently low so that the armatures of relay 107 will remain open.

20 A condenser 415 is likewise bridged between the control grid and cathode of tube V_4 . This capacity, together with resistors 413 and 414, provides a circuit having a time constant suitable to provide the required time delay action in the operation of relay 107. This time delay is to prevent false operation of relay 107, as previously described.

25 A feed back circuit comprising a resistor 416 and a capacity 417, in series, is provided between the anode of tube V_2 and the control grid of tube V_3 , for a purpose hereinafter to be explained. 30 This circuit may alternatively extend between other specific elements of the tubes to be so coupled, e. g. from the grid of V_2 to the anode of V_3 , as shown in Fig. 4 (a). The usual voltage dropping resistors and by-pass condensers used 35 in conjunction with the proper excitation of electronic tubes V_2 , V_3 and V_4 are indicated, as well as cathode heating circuits for these same tubes. The energy supply for such circuits may conveniently be secured from the power supply unit 40 shown in Fig. 5 and it is thought unnecessary to discuss in detail these elements well-known in the electronic art.

45 The operation of this receiver is best understood by first considering the action when a ringing signal of voice frequency is being received, and with the assumption that no other interfering frequencies are present upon the transmission line. Under such conditions, the major amount of the received energy will be transmitted through path 50 A (denoted by arrow A) and will cause the anode current of tube V_2 to decrease in value, thus increasing the potential at the control grid of tube V_4 , by making the grid less negative. This, in turn, increases the anode flow to tube V_4 , through the winding of relay 107, thus operating this relay. The feed back path, comprising elements 416 and 417, will then function to make the control grid on tube V_3 more positive, thus increasing the anode current of this tube and thus tending to drive the cathode of tube V_4 less positive, which is equivalent to still further decreasing the negative bias on the control grid of tube V_4 , thus affording a regenerative amplification of the effect already produced directly in tube V_4 , by the change of value of the anode current of tube V_2 .

55 The operation of the receiver may now be considered when speech transmission is occurring upon the line, during which time random frequencies corresponding to the predetermined ringing frequencies may be encountered. Under such

conditions, energy will be transmitted through both paths, A and B. The energy passing through path A will be substantially solely that at the predetermined ringing frequency, while the energy passing through path B will be that at substantially all the other speech frequencies present upon the line, as well as some random energy at the ringing frequency. It will be evident that the energy represented by the sum of the frequencies other than the ringing frequency, will be much greater than the energy passing through path A. This brings it about that detector tube V₃ will undergo a reduction in anode current, which will, in turn, increase the potential upon the cathode of tube V₄, this being equivalent to an increase in the negative grid bias of the latter tube, thus tending to reduce the flow of anode current through relay 107. This effect brings it about, then, that under these conditions relay 107 will maintain the armatures thereof retained in their respective open positions, since the effect of the energy transmitted through path B in reducing the anode current of V₄ will be much greater than the effect of a relatively smaller amount of energy passing through path A, which latter energy would tend to excite relay 107.

The cathodes of tubes V₁ and V₃ are normally grounded through contact k at armature 3 of relay 108. When a signal is being transmitted on the line, this relay is operated, as described in connection with Fig. 1, and the ground is removed from the cathodes of these two tubes, thus rendering the receiver inoperative while such signal is being transmitted.

A negative bias voltage on the grid of V₄ is required so that substantially no plate current will flow through the relay winding when no signal is being received. In this receiver, the required grid bias is obtained by adjusting the variable resistance 412 so that there will be a difference of potential between the plate of V₂ and the plate of V₃, and in such direction that the plate of V₂ is negative with respect to the plate of V₃. This adjustment is made at a time when no signals of any description are being received from the line. The bias voltage developed between the plates of V₂ and V₃ is applied to the grid and cathode of V₄ through resistors 413 and 414.

One of the requirements for the network is that the impedance looking into the network at the input terminals shall be substantially minimum at the predetermined signal frequency. In the ideal case, the impedance would be zero. If the network input impedance is very low at the signaling frequency, the voltage across such terminals will be negligible at this frequency. This is a necessary condition in order that voltages of the predetermined signal frequency will not be applied to the guard circuit and prevent proper operation of the receiver, and is shown at point 703 of curve 700.

Another requirement for the network is that the frequency output voltage characteristic should reach a maximum at the predetermined signal frequency as shown at point 702 of the curve 701 of Fig. 7.

The network shown in Fig. 4 fulfills the above requirements in a satisfactory manner if the relationship between the network elements are satisfied as described below.

Referring to Fig. 4, the network may be considered for convenience of explanation to have three sections as will be apparent to those skilled in the art. In order to satisfy the requirement that the input impedance shall be minimum at the pre-

determined signal frequency, the theoretical values of inductance and capacitance for the input section is given by the relation:

$$6. \text{ Formula 1. } \frac{1}{2\pi\sqrt{L_1(C_1+C_5)}} = f$$

In this formula, L₁ and C₁ refer to the inductance and capacitance elements of the tuned circuits of Fig. 4. C₅ represents the input coupling condenser and f is the predetermined signal frequency. When this relationship is satisfied, the reactance of the first section, looking in at the input terminals is zero.

Even though the input reactance is made equal to zero, an undesirable voltage at the signal frequency may be developed across the input terminals if the first coil of the filter has appreciable resistance, and of course, any physical coil must have some resistance. In order to mitigate the effects of any residual voltages of predetermined signal frequency appearing across terminals a-b caused by resistance in the coil, the effective gain of the guard circuit is reduced by the potentiometer arrangement of resistors 405 and 406. This allows only a fraction of the undesired voltage to become effective in the guard circuit. The resistance ratio of 405 to 406 is adjusted so that the fraction of the undesired voltage of predetermined signal frequency appearing across the input terminals is not great enough to cause an appreciable change in the plate current of V₃ when the signal frequency is applied to the receiver.

The requirement that the output voltage shall be maximum at the predetermined signal frequency can be met by

$$35. \text{ Formula 2. } \frac{1}{2\pi\sqrt{L_2C_2}} = f$$

40, where L₂, C₂ refer to the elements shown in Fig. 4 and f is the predetermined signal frequency.

In Formulae 1 and 2, the assumption is made that when the input and output sections are connected together by coupling condenser C₃ that the separate performance of the input and output sections will not be modified to any great extent by this coupling. This will be substantially true if the reactance of C₃ is made very large by comparison to the other reactances in the network. It was also assumed that the reactance of condenser C₄ is made very small by comparison to any impedances which may be subsequently connected across the output terminals. In the practical case, these assumptions can be justified.

55. In general, a number of other network configurations can be substituted in the receiver in place of the one shown in Fig. 4, for example, the one shown in Fig. 4(b) has been made to work. In all cases, however, the networks have been chosen and designed so that the input reactance is substantially zero at the predetermined signal frequency. In all cases, advantage is taken of the peculiar frequency vs. input voltage characteristics of the network to actuate the 60. guard circuit and, simultaneously, advantage is taken of the frequency vs. output voltage characteristics of the same network to operate vacuum tube V₂ in path A.

It will be noted that the receiver here described 70 is not dependent for its operation upon the utilization of a modulated voice frequency ringing signal current, but will be operated by a continuous ringing signal current at the predetermined voice frequency. While the presence of the 20 cycle modulation renders desirable the

special feedback circuit from the screen grids of tubes V_2 and V_3 to the anode of tube V_1 , yet it often is desirable to use such modulation when employing this invention in conjunction with certain other signaling systems which latter do employ such modulated voice frequency ringing currents. The fact that the receiver will operate on such continuous signaling current affords the further advantage that it may be employed in transmission networks employing such modulated voice frequency ringing currents, even if, as frequently happens, the current intervals due to the modulation tend to fill up from reflected currents on the line or from other causes. At low power levels the 20 cycle modulated current may tend to cause chattering of relay 107, but the feedback action caused by the fact that the screen grids of tubes V_2 and V_3 secure their feed from the anode of V_1 , instead of directly from the power supply, tends to remove or minimize such difficulty.

To change the receiver so as to operate on some other predetermined ringing frequency, it is merely necessary to change switch 407' from one position to the other, which will change the inductances and capacities found in the various filter elements disposed along the interstage network of transmission path A. As previously explained, the oscillator frequency should be simultaneously changed, which may readily be accomplished by a mechanical coupling of switch 407' to switch 312 (Fig. 3). The oscillator output will, of course, at the same time be suitably changed by suitable adjustments of the network 310', as by changing switch 350 thereof, as shown in Figs. 3 and 6, in a manner which will be apparent to one skilled in the art. All the switches just mentioned may be mechanically intercoupled, if so desired, to facilitate switching operations.

The manner in which the operation of relay 107 by the receiver just described, causes the actuation of the drop or other signaling device at the receiving switchboard, has been described in connection with Fig. 1, and, briefly stated, consists of the connection of a supply of 20 cycle energy directly to such signaling device. At the same time it will be noted that the line is disconnected at armatures 1 and 2 of relay 107, so that undesired energy will not be transferred back to the line. While not being confined to the use of any special type of electronic tube, the type commercially known as 6G6-G has been found suitable for use as tubes V_1 , V_2 , V_3 and V_4 of Fig. 4, when the various elements there shown have the values indicated.

In Fig. 5 there is shown a power supply unit used in connection with a complete ringer assembly, according to this invention, and affording all the electrical energy required, both A. C. and D. C., and of various frequencies and voltages, for the operation of such complete ringer assembly. This power supply is adapted for operation from a commercial A. C. supply of any conventional voltage between 100 and 250, although by suitable changes apparent to those skilled in the art, energy supplies of other type may be employed. As one alternative supply, there is shown the necessary switching and conversion apparatus to enable the power unit to be operated from 12 volts D. C., such as may readily be obtained from a battery or the like.

The power unit supplies its output to a series of terminals shown at the right side of Fig. 5 and numbered 1 to 10, serially. Terminals 1

and 2 supply 180 volts D. C. with the negative side grounded. Terminals 3 and 4 supply 75 volts D. C. free from any ground connection, as is necessary for the cathode-anode supply of tube V_4 , shown in Fig. 4. Terminals 5 and 6 supply 6.3 volts A. C. for the cathode heating circuits of the various tubes employed in this invention. Terminals 7 and 8 supply the 20 cycle ringing current at approximately 80 volts. Terminals 9 and

10 correspond with those similarly numbered in Fig. 3 and afford connection between the voice frequency electronic oscillator shown at the right of Fig. 3 and the mechanical vibrator shown at the left of Fig. 3 and also at the bottom right hand of Fig. 5.

A transformer 304, of which a portion is indicated at the extreme left of Fig. 3, is supplied with a plurality of windings. One terminal 501 is connected through a suitable fuse 502 and switch 503 to a common terminal 504. Various taps 505, 506, 507 and 508 are taken from one primary winding 509 of the transformer, and are for connection to the various mains-voltages indicated in Fig. 5. The throwing of switch 503 to the left will then energize the primary winding of transformer 304.

Secondary winding 501, bridged by a suitable capacity 511, feeds rectifier 512, the D. C. output of which is filtered by capacities 513 and 514 and inductance 515, being delivered to output terminals 1 and 2.

The output of secondary winding 516, similarly is rectified by element 517 and filtered by condenser 518 and resistor 519, the output appearing on terminals 3 and 4.

Secondary winding 520, supplies 6.3 volts A. C. for cathode heating purposes and is provided with a suitable regulating resistance 521, controlled by the action of switch 503.

Secondary winding 522 is identical with the secondary winding shown at the left of Fig. 3 and the rectifier, filter, vibrator, transformer and other elements shown connected to winding 522 and to one another, are identical with the similarly numbered elements in Fig. 3, at the left of the dotted line and bear identical reference numerals. As explained in connection with Fig. 3, vibrator 301 serves not only to supply 20 cycle current at terminals 7 and 8, corresponding with terminals 309 of Fig. 3, but also acts to determine the modulation of the electronic oscillator shown at the right of Fig. 3, by changing the negative bias thereupon, as explained in connection with the description of Fig. 3.

To operate the power supply unit of Fig. 5 from a 12 volt D. C. source such as a battery, switch 503 is thrown to the right. This connects the battery with a mechanical vibrator 523, via a suitable capacity-inductance filter system 524, as is well-known in the art. The output of vibrator 523 is fed to a mid-tapped primary winding 525, of transformer 304, thus exciting all the secondary windings of the transformer in the same manner as previously described when primary winding 509 was excited from the mains voltage. The connection of the power supply unit with the other units of a complete ringer may conveniently be made by connecting terminals 1-10 to a multi-terminal socket, with which a suitable plug and cable may be interconnected.

In Fig. 6, there are shown, connected together, a complete set of the various units except the power supply, constituting a complete ringer terminal equipment, capable both of transmission

and reception. The terminals at the lower right hand portion of Fig. 6 are numbered correspondingly with the terminals at the right side of the power supply unit shown in Fig. 5, being intended for connection therewith, although any other suitable sources of power may be employed instead of the power unit here shown. In Fig. 6 the network 310 is shown with one form of switching device which may be employed to give the various adjustments needed for a predetermined ringing frequency or power output level, as discussed in connection with Fig. 3; but other forms may be used.

The remaining elements shown in Fig. 6 correspond with those already shown and described in connection with Figs. 1-4 and bear reference numerals identical with those already employed, so that a detailed description thereof would be repetitious.

It is possible to adapt this system to signaling systems other than ringing, for example long distance telephone automatic switching and the like. Many of these long distance schemes require a receiver with a guard circuit that can be bridged across the talking line, as is done in the case of the instant invention.

Certain portions of systems already known in the art and designed to perform the same functions as the instant system, may additionally be incorporated therein. For instance, an additional filter, tuned to reject the predetermined signaling frequency may be inserted in transmission path B, still further to reduce the transmission therethrough of such signaling frequency.

Other changes and additions in our system will be apparent to those skilled in the art, and may be made without departing from the scope of the hereunto appended claims.

What is claimed is:

1. A signal receiver having the ability to discriminate between a signal of a predetermined frequency and speech signals including said predetermined frequency, including means for receiving all said signals, two transmission paths, the first path sharply tuned to said signal of predetermined frequency and the second path substantially aperiodic, means for dividing the received signals between said two paths, whereby only said signal of predetermined frequency passes to a major extent over said first path and all other frequencies pass to a major extent over said second path; means for combining the outputs of said paths to produce the difference between said outputs, means for determining the closure of a relay when the major amount of energy transmitted passes over said first path and means for determining the opening of said relay when the major amount of energy transmitted passes over said second path.

2. In signaling systems carrying both speech signals and another signal of a predetermined frequency lying within the range of speech frequencies, a receiver responsive only to said other signal, comprising a two-channel transmission path, means for directing the major portion of said other signal over the first channel and means for directing the major portion of the speech signals over the second channel, a de-modulator at the termination of each channel, means for combining the respective de-modulated outputs of both channels to produce the difference of said outputs, relay means normally unoperated but capable of actuation by the combined outputs and responsive to the relative energy in the respective outputs, whereby greater energy in said first

channel will operate said relay means, while greater energy in said second channel will maintain said relay means unoperated.

3. Device according to claim 2, in which said other signal and speech signals directive means includes an electron relay, the combined signals being fed to the grid thereof and including a current dividing network in the anode circuit thereof, said respective channels being connected to different portions of said anode network.

4. Device according to claim 2, in which said first channel includes a resonant network tuned to pass substantially only said other signal, while said second channel possesses substantially aperiodic pass characteristics per se, but the interconnection of said two channels causes said second channel to have virtual band rejection characteristics.

5. Device according to claim 2, in which said relay means includes an electron relay having an electro-magnetic relay in the anode circuit thereof, said electron relay being normally negatively biased to reduce the anode current sufficiently to maintain said electro-magnetic relay in non-operative position; and means actuated by said respective outputs whereby greater relative energy in said first channel will decrease said negative bias, increase said anode current, and operate said electromagnetic relay.

6. A ringing signal receiver including means for simultaneously injecting therein a ringing signal of predetermined frequency and speech signals, means for substantially separating said ringing signal from said speech signals, including a first transmission path having high acceptance substantially solely for the ringing signal frequency, means for passing the speech signals including a second transmission path having acceptance for a broad range of frequencies, means for combining the respective outputs of both said paths to produce the difference of said outputs and relay means actuated by said difference only when the energy passing through said first path is substantially greater than the energy passing through said second path.

7. Device according to claim 6, in which said means for differentially combining the respective outputs of both paths includes two detector tubes, one fed from each of said paths, a resistance network connected to the anodes of both tubes, an output tube having the grid and cathode thereof connected to points on said network so chosen that when no signals are received, said grid will be negatively biased, whereby signals received over said first path will tend to drive said grid positive and actuate said relay means, while signals received over said second path will tend to maintain said grid negative.

8. Device according to claim 6, wherein the input to said means for differentially combining the outputs of said paths includes a resistance-capacitance network having a time constant sufficiently great to prevent response to received signals of relatively short time duration.

9. The method of receiving a signal of a predetermined frequency when the line carrying said signal is also carrying speech signals including said frequency, which includes the step of dividing the energy from said line into two channels, attenuating all frequencies except said predetermined frequency in the first channel, passing substantially all speech frequencies except those proximate to said predetermined frequency, with uniform attenuation through the second channel, combining the outputs of said channels to

produce the difference of said outputs, determining which channel is passing the greater amount of energy and actuating a detector for the signal of predetermined frequency only when the greater amount of energy is passing over said first channel.

10. Device according to claim 2, and also including a capacity connected in shunt to the input of said means for differentially combining said de-modulated outputs, whereby response to said relay means to transient frequencies is hindered.

11. Device according to claim 2, in which said de-modulators are electronic detector tubes and in which a regenerative feed-back path is supplied from a first element of the detector tube of said first channel to a second element of the detector tube of said second channel, said second element being opposite in phase to said first element, whereby the differential of the respective outputs is increased, for a given input to the grid of the detector tube of said first channel.

12. A signal receiver including means for simultaneously injecting therein a signal of predetermined frequency and speech signals, means for separating said signal of predetermined frequency from said speech signals, including a first transmission path having high acceptance substantially solely for the signal of predetermined frequency, means for passing the speech signals including a second transmission path having acceptance for a broad range of frequencies, means for combining the respective outputs of both paths to produce the difference of said outputs, including two detector tubes, one fed from each of said paths, two resistors of approximately the same values of resistance connected one in series with the anode circuit of each tube, means for varying the value of one of said resistors so that the normal relative potentials of the two anodes can be adjusted to be slightly different from one

5 another, a common feed for the two anodes and an output tube having the grid and cathode thereof connected to the respective anodes so that when no signals are received, said grid will be negatively biased, whereby signals received over said first path will tend to drive said grid positive and actuate said relay means, while signals received over said second path will tend to maintain said grid negative.

10 13. Device according to claim 12, and also including two resistors, one connected between the anode of one of said detector tubes and the grid of said output tube and the other connected between the anode of said other detector tube and the cathode of said output tube, and a capacity shunting the cathode and grid of said output tube, whereby relative persistence of input energy is necessary in order to actuate said output tube.

15 14. A signal receiver for receiving both signal and speech frequencies, responsive to a signal of a predetermined frequency, including means for discriminating against operation by speech frequencies which include said predetermined frequency, said means including two transmission paths and a reactive network for diverting the energy of a narrow band of frequencies including said predetermined frequency into the first path, and for diverting substantially all other frequencies into the second path, said reactive network transmitting said narrow band of frequencies with small attenuation and presenting a relatively small input impedance to said narrow band of frequencies.

20 30 35 15. Device according to claim 2, in which said de-modulators are electronic tetrodes and in which the screen-grids of said tetrodes are coupled back to the input of said two-channel transmission path so as to secure regenerative effects

WILLIAM GIBSON STANLEY.
